DESIGN FOR A HAMMER HEAD

Walter W. Rector, Cleveland, Ohio, assignor to
The American Fork and Hoe Company, Cleve-
land, Ohio, a corporation of Ohio

Application June 19, 1941, Serial No. 101,570

Term of patent 14 years

To all whom it may concern:

Be it known that I, Walter W. Rector, a citizen of the United States, residing at Cleveland, in the county of Cuyahoga and State of Ohio, have invented a new, original, and ornamental Design for a Hammer Head, of which the following is a specification, reference being had to the accompanying drawing, forming a part thereof, in which:

Fig. 1 is a side elevational view of a hammer head showing my new design;

Fig. 2 is a top plan view slightly in perspective of the hammer head of Fig. 1;

Fig. 3 is a bottom plan view slightly in perspective of the hammer head of Fig. 1; and

Fig. 4 is a sectional view taken from the line 4—4 of Fig. 1.

I claim:

The ornamental design for a hammer head, substantially as shown.

WALTER W. RECTOR.
